UNITED STATES PATENT OFFICE.

ALBERT J. SAYERS, OF CHICAGO, ILLINOIS, ASSIGNOR TO LINK-BELT COMPANY, OF CHICAGO, ILLINOIS, A CORPORATION OF ILLINOIS.

COAL-WASHER.

1,142,060.

Specification of Letters Patent.

Patented June 8, 1915.

Application filed August 29, 1913. Serial No. 787,254.

To all whom it may concern:

Be it known that I, ALBERT J. SAYERS, a citizen of the United States, residing at Chicago, in the county of Cook and State of Illinois, have invented a certain new and useful Improvement in Coal-Washers, of which the following is a specification.

My invention relates to coal washers and has for its object to provide means as hereinafter set forth.

The invention is illustrated in one form in the drawings hereto attached, wherein—

Figure 1 is a cross section; Fig. 2 is a vertical section of the jig pan on the line 2—2 of Fig. 1; Fig. 3 is a detail section of the jig pan on the line 3—3 of Fig. 1; Fig. 4 is a horizontal section on the line 4—4 of Fig. 1; Fig. 5 is a detail of the removable gate; Figs. 6 and 7 are sections showing further details of said gate.

Like parts are indicated by the same letters in all the figures.

A, A are the sides and partitions which form the two-part tank B, C which parts are connected through the chute C¹ and the jig. In the chute, jig and tank the water stands at an approximately uniform and common level.

D is the jig having the bottom D¹ inclined and preferably perforate. It also has the downwardly projecting parts or walls D² which form an inertia chamber wherein a very considerable quantity of water is held in position so that when the jig descends the water may pass freely up through the perforations of its inclined bottom.

D³ is a slate opening at the forward edge of the perforated bottom D¹ and it opens into a vertical chute D⁴ which consists of the outer wall D² of the inertia chamber, a wall D⁵ and between the two, inclined walls D⁶, D⁷. This chute or outlet is thus larger at the top than at the bottom and it is capable of receiving slate from the bottom of the jig and carrying it down through a contracting chute or opening outlet and discharging it into the inertia chamber. This outlet is formed so as to have a closed pocket D⁷ above. This pocket is roofed or covered by the clean coal chute E which discharges into the chute C¹ so that the clean coal passes into the tank C.

The inertia chamber may be guided and kept in position in any desired manner, as for example, by the rollers F, F on the

brackets F¹, F¹ and F², F², these latter for convenience projecting from the back plate or beam F³, which is secured by means of the cross beams F⁴ to the shell or side A of the tank.

G is a coal inlet chute which preferably discharges into the opening G¹ at the back or higher part of the jig so that as the coal flows over the chute G it is discharged through the opening G¹ into the jig and passes laterally thereacross and therethrough. The jig, however, being in vertical reciprocation, causes the coal, as herein-after described, to separate into strata and the upper or fine coal passes out over the chute C¹ into the tank C, whence it is recovered in any desired manner while the slate passes from the slate outlet D³ into the refuse chamber or discharge outlet D⁴, whence it passes into the inertia chamber.

J, J are beams which support the shaft J¹ driven from the pulley J² and provided with eccentrics J³ on each end from which passes a rod J⁴ to the side of the jig. The rotation of the shaft and eccentrics causes the jig to vertically reciprocate.

K is a slate or refuse gate adapted to close or vary the size of the refuse discharge opening from the jig to the refuse chamber. It is connected by a rod K¹ with the lever arm K² on the shaft K³ associated with the handle K⁴ carrying the thumb piece K⁵, the spring controlled rod K⁶, which is adapted to engage the circular rack K⁷ on a wall K⁸ which is mounted on the shaft K³, and thus by manipulating the handle the gate can be locked in any desired position. The gate K consists of a flat perforated plate the edges of which are received between vertical guide strips M, M projecting from the jig wall M¹. This plate has an opening at M² which by variation of its position controls the effective opening from the jig into the refuse chamber. This gate is downwardly projecting so as to control an opening N in the lower end of the refuse chamber when that chamber is closed by the inclined bottom N¹ as shown in Fig. 6. This is a modified form of structure intended to make it possible to cut off the access of all water from the inertia chamber to the jig by way of the refuse chamber. The gate indicated in Figs. 6 and 7 by K¹¹ is controlled for both purposes by operating the handle. While these drawings present the structure of a working machine,

I do not wish to be limited to these particular details, since they might be greatly varied.

The essential point is that the structure 5 should contain in a still water jig means for choking down or wholly cutting off the flow of water from the inertia chamber upwardly through the refuse chamber and laterally into the jig.

10 The use and operation of my invention are as follows: Coal washers may be roughly divided into three classes: those containing fixed jigs, those containing reciprocating jigs which are operated in a continuous 15 stream of water and those which have jigs reciprocating in still water. These three classes will include most, if not all jiggling coal washers. The washer of this application is in the third class. The material to 20 be separated or washed is moved laterally or horizontally in a comparatively thin layer through and substantially beneath the surface of a body of still water. The lateral motion is due to the pressure of the oncoming 25 stream of material. The separation is effected by gravity, for the problem deals with materials of differing specific gravity which have been mixed together. To effect 30 this separation the moving mass of material is loosened by reciprocating it vertically as it passes along against a confined body of water, all of the upwardly moving streams from which confined body of water are directed upwardly through the moving mass 35 being substantially uniformly distributed therethrough. As the mass moves under these conditions it is separated into two layers of unequal specific gravity, the lighter being discharged outside of the jig and the 40 immediate jig tank, while the heavier is discharged into the confined body of water whereby disturbances, inequality of action and irregularity of stream movement in the water which is being utilized to loosen the 45 bed is obviated.

In coal washers of the type wherein the 50 jig is reciprocated in still water, it is important for effective operation that substantially all of the water which tends to move toward the jig when it descends should be 55 directed through the bed of material in the jig and be discharged upwardly through the bed in relatively parallel streams which are comparatively uniformly distributed 60 through the bed. Cross streams or disturbing or conflicting streams or currents are to be avoided and any tendency of any such water to pass through a portion of the bed and then escape without entirely traversing 65 the bed is very injurious to its action. Since the separation by gravity which is relied upon, is due to the loosening of the bed or its vertical spread, it is obvious that every effort should be made to prevent disturbances or deflection of the vertical stream or

streams of water passing upwardly through the bed. In types of machines like that illustrated in the drawings where provision is made for the lateral discharge of refuse, for example, slate, a disturbance of the flow 70 of water through the jig will occur if there is any escape for the water which tends to move toward the jig through the slate opening or channels or passages connected therewith or if there is any tendency for any considerable or excess amount of water to enter the jig laterally through the slate opening. To avoid these difficulties the slate chamber is placed at the side of the jig and is connected therewith. It is closed at the top but 80 open at the bottom into the inertia chamber or confined water chamber below the jig. When the parts are so arranged all of the water which tends to move toward the jig either passes up through the bed in the desired manner or passes up through the slate chamber and then somewhat laterally through the slate opening into the bed. This latter is necessarily a disturbing stream of 85 water tending to deflect or disturb the vertical streams of water immediately inside the slate opening and to deaden the bed and even force some of the refuse matter up into the coal discharge. These evils in such an arrangement are of course variable being of 90 little consequence in some forms of structures and with certain materials but in some instances being of great importance and highly unsatisfactory to the operation of the machine. To obviate these dangers I have 95 provided a throttling means for slowing down or even cutting off the flow of water through the slate chamber and slate opening toward the jig. I accomplish this by 100 extending the slate chamber downwardly 105 into the inertia chamber and by hoppering it or reducing its cross-sectional area so that the tendency will be to minimize the upward flow of water through the slate chamber. This tendency will be increased if the conditions are such that the slate tends to more or less clog or obstruct the lower part of 110 the chamber, and in a modification I have provided means for closing at least during a portion of the operation the lower end of 115 the slate chamber so that for a period of time during the operation of the machine, it will absolutely cut off the flow of water through the slate chamber. The result of 120 these devices and arrangements is to minimize or practically suppress the lateral and disturbing currents of water entering the jig through the slate discharge opening and the coal washer operates by forcing the entire body of water which tends to move toward the jig from the inertia chamber to traverse the bed of material in jets or streams, due to the perforations in the bottom of the jig, in a generally upwardly direction substantially parallel to the vertical 125 130

or to each other. This is the ideal condition for efficiency in the case of apparatuses of this kind.

In the foregoing explanation of the phenomena, I have thought of the water as moved upwardly through the perforated bottom of the jig and being discharged in streams beyond and into the mass of material, and I have thought of the material as being carried in a mass and reciprocated through the vertical motion of the jig. Another way of stating the matter which is here presented, in order that no confusion of terms may result, is as follows: When the jig bottom descends, it descends through the water, thus leaving a larger or deeper water body above the bottom of the jig and within the jig. The downward displacement of the jig bottom permits the contents of the jig to settle and the difference in specific gravity causes its various particles to descend unequally and therefore with unequal speed and to arrange themselves in strata according to their differences in specific gravity. There is little or no water flowing upwardly and entirely through the jig and out with the coal.

I claim:

1. In a washer the combination of a washing tank with a jig therein having a perforated bottom and material and refuse discharge openings at one side, means for reciprocating the jig therein, means for supplying material to the jig at a distance from the openings, an inertia chamber beneath the jig, a refuse chamber outside of the jig but connected at all times with the refuse discharge opening of the jig and connected with the inertia chamber whereby all the water from the inertia chamber is directed through the whole of the bed of material in the jig and the separated refuse is discharged into the inertia chamber and a downward extension of the refuse chamber into the inertia chamber, said inertia chamber and extension being attached to and movable with the jig.

2. In a washer the combination of a washing tank with a jig therein having a perforated bottom and material and refuse discharge openings at one side, means for reciprocating the jig, means for supplying material to the jig at a distance from the openings, a relatively deep downwardly extending inertia chamber beneath the jig, a refuse chamber outside of the jig closed above but connected at all times with the refuse discharge opening of the jig and connected with the inertia chamber whereby all the water from the inertia chamber is directed through the whole of the bed of material in the jig and the separated refuse is discharged into the inertia chamber, and a downward extension of the refuse chamber into the inertia

chamber, said inertia chamber and extension being attached to and movable with the jig.

3. In a washer the combination of a washing tank with a jig therein having a perforated bottom and material and refuse discharge openings at one side, means for reciprocating the jig, means for supplying material to the jig at a distance from the openings, a relatively deep downwardly extending inertia chamber attached to the jig and beneath the jig, a refuse chamber outside of the jig closed above but connected at all times with the refuse discharge opening of the jig and connected with the inertia chamber whereby all the water from the inertia chamber is directed through the whole of the bed of material in the jig and the separated refuse is discharged into the inertia chamber and a downward extension of the refuse chamber into the inertia chamber, said extension being connected to and movable with the jig.

4. In a washer the combination of a washing tank with a jig therein having a perforated bottom and material and refuse discharge openings at one side, means for reciprocating the jig, means for supplying material to the jig at a distance from the openings, a relatively deep downwardly extending inertia chamber beneath the jig, a refuse chamber outside of but attached so as to reciprocate with the jig and connected with the refuse discharge opening of the jig and the inertia chamber whereby all the water is directed through the whole of the bed of material in the jig and the separated refuse is discharged into the inertia chamber, and a downward extension of the refuse chamber into the inertia chamber, said extension being connected to and movable with the jig.

5. In a washer the combination of a washing tank with a jig therein having a perforated bottom and material and refuse discharge openings at one side, means for reciprocating the jig, means for supplying material to the jig at a distance from the openings, a relatively deep downwardly extending inertia chamber attached to the jig and beneath the jig, a refuse chamber outside of but attached so as to reciprocate with the jig and connected with the refuse discharge opening of the jig and the inertia chamber whereby all the water is directed through the whole of the bed of material in the jig and the separated refuse is discharged into the inertia chamber, and a downward extension of the refuse chamber, said extension being connected to and movable with the jig.

6. In a washer the combination of a washing tank with a jig therein having a perforated bottom and material and refuse discharge openings at one side, means for reciprocating the jig, means for supplying ma-

terial to the jig at a distance from the openings, an inertia chamber beneath the jig, a refuse chamber outside of the jig but connected with the refuse discharge opening of the jig and the inertia chamber whereby the water is directed through the whole of the bed of material in the jig and the separated refuse is discharged into the inertia chamber and a downwardly projecting continuation of the refuse chamber with downwardly diminishing cross section for the purpose of throttling the flow of water through the refuse chamber into the jig.

7. In a washer the combination of a washing tank with a jig therein having a perforated bottom and material and refuse discharge openings at one side, means for reciprocating the jig, means for supplying material to the jig at a distance from the openings, an inertia chamber beneath the jig, a refuse chamber outside of the jig but connected with the refuse discharge opening of the jig and the inertia chamber whereby the water is directed through the whole of the bed of material in the jig and the separated refuse is discharged into the inertia chamber and a downwardly projecting continuation of the refuse chamber with downwardly diminishing cross section for the purpose of throttling the flow of water through the refuse chamber into the jig and means for entirely cutting off such flow of water.

8. In a washer the combination of a washing tank with a jig therein having a perforated bottom and material and refuse discharge openings at one side, means for reciprocating the jig, means for supplying material to the jig at a distance from the

openings, an inertia chamber beneath the jig, a refuse chamber outside of the jig but connected with the refuse discharge opening of the jig and inertia chamber whereby all the water is directed through the whole of the bed of material in the jig and the separated refuse is discharged into the inertia chamber, a downward extension of the refuse chamber into the inertia chamber and means for cutting off the flow of water upwardly from the inertia chamber through the refuse chamber into the jig, said extension being connected to and movable with the jig.

9. In a washer, the combination of a washing tank with a jig therein having a perforated bottom and material and refuse discharge openings at one side, an inertia chamber beneath the jig, a refuse chamber outside of the jig but connected with the refuse discharge opening of the jig and connected also with the inertia chamber whereby all the water from the inertia chamber is directed through the whole of the bed of material in the jig and the separated refuse is discharged into the inertia chamber, and means between the refuse chamber and the inertia chamber for throttling the backward flow of water from the inertia chamber through the refuse chamber into the jig.

In testimony whereof, I affix my signature in the presence of two witnesses this 23rd day of August 1913.

A. J. SAYERS.
